UNITED STATES PATENT OFFICE.

JAMES F. MAYS, OF LEXINGTON, NORTH CAROLINA, ASSIGNOR OF ONE-FOURTH TO
A. M. KISTLER, OF MORGANTON, NORTH CAROLINA, AND ONE-FOURTH TO D. E.
RHYNE, OF LINCOLNTON, NORTH CAROLINA.

CALCULATING MACHINE.

Application filed May 3, 1922. Serial No. 558,156.

To all whom it may concern:

Be it known that I, JAMES F. MAYS, a citizen of the United States, residing at Lexington, in the county of Davidson and State of North Carolina, have invented a new and useful Calculating Machine, of which the following is a specification.

This invention relates to calculating or adding machines and the like and has for its object the simplification of the mechanism by eliminating many of the parts heretofore found necessary in structures of this character. In the type of machine disclosed in prior patents issued to me, as for example No. 1,323,894 dated Dec. 2, 1919, it has been necessary to employ a group of levers for each column of keys carried by the machine, these levers serving to transmit motion to a rock shaft controlling the actuation of the dial mechanism. It is an object of the present invention to provide a machine in which a single lever can be actuated by all the keys in a single column, this lever transmitting motion through a master key to the aforesaid rock shaft.

It is another object of this invention to render more compact and efficient the construction of the escapement mechanism employed for controlling the action of the dial. Heretofore this mechanism has required the use of resiliently held fingers or pallets cooperating with a "floating" wheel in turn combined with a "carry" wheel as disclosed, for example, in Patent No. 1,165,337 issued to me on Dec. 21, 1915. It has been found however, that the resiliently held fingers, or pallets do not give the uniformly accurate and perfect movement which is necessary in an escapement of this kind. The lack of perfect accuracy, and rigidity under strain, is caused by the double movement of the flexible fingers. They have a movement up and down, and also forward and backward.

It is the purpose of my present invention to provide fingers or pallets of a single piece of metal, designed for an up and down movement only, and adapted to operate with extreme accuracy and to be absolutely rigid under the strain of holding the floating wheel.

A further object is to provide separate pallets of the kind mentioned which operate

alternately and are positioned for engagement with opposed portions respectively of the floating wheel, thus to work freely and positively to insure accurate stopping of the wheel.

A further object is to provide the dial mechanism with novel control mechanism whereby the "carry" wheel is held securely and positively against movement between required operations thereof.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a longitudinal section through a calculating machine embodying the present improvements and showing one column of keys and the dial mechanism.

Figure 2 is a plan view of a portion of the keyboard.

Figure 3 is a perspective view of a portion of one of the keys.

Figure 4 is an enlarged section on line 4—4, Figure 1.

Figure 5 is a section on line 5—5, Figure 4.

Figure 6 is a section on line 6—6, Figure 4.

Figure 7 is a side elevation, partly in section, of the structure shown in Figure 6.

Figure 8 is a section on line 8—8, Figure 4.

Figure 9 is an enlarged section on line 9—9, Figure 4, the shafts being shown in elevation.

Figure 10 is a section on line 10—10, Figure 9.

Figure 11 is a section on line 11—11, Figure 9.

Figure 12 is a section on line 12—12, Figure 9 the carry wheel being shown in elevation.

Figure 13 is a section on line 13—13, Figure 4.

Referring to the figures by characters of reference 1 designates the casing or hous-

ing of the machine in the top of which are mounted parallel columns of keys 2 mounted for up and down movement and each of which is provided with the usual head 3 on which a number is displayed. The numbers on the keys of each column range from "1" to "9" so that there are nine keys in each column arranged in proper numerical succession. Each of the keys is yieldingly supported by a spring 4 as shown in Figure 9 and the upward movement of each key is limited by a pin 5 engaging the top of the casing or housing while the downward movement is limited by a shoulder 6 engaging a guide strip 7.

Arranged along one side of the keys of each column is a lever 8 preferably fulcrumed at one end as shown at 9. The lever is yieldingly supported by a spring 10 and normally bearing on the lever are pins or projections 11 extending from the keys 2.

All of the keys have substantially the same length of movement when depressed but in view of the fact that the keys are located at different distances from the fulcrum of the lever 8 it will be obvious that each key will produce a different throw of the lever. For example the key nearest the free end of the lever will, when depressed, swing the lever through a smaller arc than will the next adjoining key while the greatest movement of the lever will be caused by the depression of the rear key of the column.

35 A master key 12 is adapted to be actuated by the lever 8 and any suitable means may be employed for transmitting motion from this master key to a rock shaft 13 arranged longitudinally within the casing or housing 1. For example a segmental gear 14 can be secured to the rock shaft and receive motion from a rack 15 carried by the master key 12.

45 A spring 16 serves to hold the rock shaft normally in a predetermined position and secured to this rock shaft is a segmental gear 17 constantly in mesh with a gear 18 formed at one end of a sleeve 19. An annular flange 20 is provided at the other end of the sleeve and has an arcuate slot 21. Sleeve 19 is mounted for rotation on a spool 22 formed at one end with a flange 23 from which a pin 24 extends, this pin projecting through and is adapted to work within the slot 21. On the other side of the flange 23 is another pin 25 forming the fulcrum of a pawl 26 engaging an internal ratchet 27 secured to and rotatable with a shaft 28. This shaft extends through the spool 22 and when the ratchet 27 is rotated in one direction by the pawl 26 the shaft necessarily rotates therewith. A spring 29 shown in Figure 11 serves to hold the pawl normally pressed into engagement with the ratchet 27.

An annular flange 30 is provided at the other end of the spool 22 and fulcrumed on one face thereof is a spring controlled dog 31. A slot 32 is formed in the flange 30 and movably mounted therein is a pin 33 extending from the dog 31. Another cam slot 34 is formed in a disk 35 arranged in front of flange 30 and adapted to rotate with the gear 18. Thus it will be seen that relative movement of flange 30 and disk 35 will result in outward or inward movement of the dog relative to the shaft 28. A toothed wheel 36 is secured to the shaft 28 and is adapted to be engaged by the dog 31. A stop pin 37 is carried by the flange 30 and normally bears against a lug 38 so as thus to hold the rotatable parts at the proper starting point when set.

The mechanism mounted on the shaft 28 and which has heretofore been described does not in itself constitute any part of the present invention but is covered by Letters Patent heretofore issued to me. It constitutes a lost motion driving connection very essential in machines of this character whereby the dog 31 will be caused to engage with the toothed wheel 36 before the actuation of the slotted flange 23.

The shaft 28 extends through a sleeve 39 suitably supported, as by means of a bar 40, this sleeve being held against rotation and constituting a firm support for the escapement mechanism. This escapement mechanism includes a carry wheel 41 which, as shown in Figure 12, has peripheral recesses 42 regularly spaced. A hub 43 is extended laterally from the center of the wheel 41 and aligns with a corresponding hub 44 extending laterally from a drive wheel or gear 45. This gear meshes with 105 and is adapted to be actuated by a smaller gear 46 receiving motion through gears 47 and 48 from the shaft 28 of the next adjoining unit of the lower order, it being understood that gears 46 and 47 rotate in 110 unison.

Mounted for rotation on the aligning hubs 43 and 44 is the hub 49 of a floating wheel 50. This wheel is provided at its periphery with oppositely extending stop projections or lugs 51 regularly spaced, the lugs on one side of the wheel being opposite the centers of the spaces between the lugs on the other side of the wheel. This staggered arrangement is shown clearly in 120 Figure 5. These lugs or projections 51 divide the periphery of the floating wheel into ten equal parts and formed within the floating wheel is an arcuate slot 52. Extending loosely through this slot and adapted to move therein through an arc of 36° is a pin 53 projecting from one face of the carry wheel 41. A coiled spring 54 is attached at one end to this pin 53, is partly wrapped about the hub of the floating wheel 130

50, and is attached at its other end to a pin 55 extending from the gear 45. Another, lighter spring 56 is attached to the pin 53 and is partly extended around the hub of the floating wheel 50 and secured to said wheel as indicated at 57. The two springs are oppositely disposed as shown in Figure 5.

A pivot stud 58 is arranged adjacent the shaft 28 and has mounted on it a pair of levers 59 constituting pallets. Each of these levers is formed at one end with a projection 60 adapted to extend into the path of one set of lugs or projections 51 on the floating wheel, it being understood that the two pallets are spaced apart a sufficient distance to receive the wheel between them. Those ends of the levers or pallets 59 remote from the projections 60 bear against the peripheries of rotary cams 61 and are held thereagainst by springs 62. Each cam is substantially circular for the greater portion of its circumference but has a short eccentric portion extending inwardly and terminating at a radial shoulder 63. The shoulders on the two cams are oppositely disposed so that during each complete rotation of said cams the shoulders 63 will be brought past the adjacent ends 30 of the levers or pallets 59 respectively at regular intervals. Each time a shoulder moves past one of these pallets or levers the spring 62 connected thereto will actuate the pallet or lever so as to shift the projection 60 out of the path of one set of projections 61. At the same time the eccentric portion of the other cam will be moving the projection 60 of the second lever or pallet into the path of one of the projections 51 on the other side of the floating wheel. Thus it will be seen that the two pallets will operate alternately in properly timed relation to release the wheel and to positively stop it after the 45 wheel has moved through one-tenth of a circle.

A gear 65 secured to the cams 61 receives its motion through a gear 66 from the shaft 28 of the adjacent unit of the lower order 50 and on which the gear 48 is mounted.

The rock shaft 13 has a collar 67 provided with a peripheral projection 68 and one arm 69 of a bell crank 70 extends to a position where it is adapted to be engaged by the extension 68 as shown in Figures 5 and 12.

The carry wheel 41 is so located that a head 71 on the bell crank 70 will project into any one of the recesses 42 to form 60 a stop but under normal conditions this head is held out of engagement with the carry wheel by the pressure of the projection 68 against the arm 69.

A control wheel 73 is secured to the 65 shaft 28 and has a series of laterally ex-

tending projections 74 regularly spaced, ten of these projections being provided. This wheel has an interior ratchet 75 adapted to be engaged by a pawl 76 (see Fig. 10) pivotally mounted on a pin 77 extending laterally from the carry wheel 41. A spring 78 serves to hold the pawl normally projected into engagement with the ratchet so that when the carry wheel is rotated clockwise the ratchet 73 and the shaft 28 75 will be moved therewith.

Normally seated in one of the notches 42 is one end of a bell crank 79 to the other end of which is pivotally connected a locking finger 80 working between spaced stop pins 81 and 82. A spring 83 serves to hold this finger yieldingly in a predetermined position relative to the bell crank. The parts are so located and proportioned that when one end of the bell crank 79 is seated in a recess 42 the free end of finger 80 is located close to but out of the path of one of the projections 74.

Each of the shafts 28 has a gear 84 meshing with and adapted to rotate a gear 85 secured between two number dials 86 and 87 which rotate as one body below two sight openings 88 and 89 respectively formed in the casing or housing 1. As shown particularly in Figure 1 the numerals on these dials are arranged in proper numerical succession from "1" to "9" and "0", the numerals on one of the dials being arranged oppositely to the numerals on the other dial so that, as shown in Figure 1 the numeral 3 on one dial will be in line with the numeral 6 on the other dial, the numerals 4 and 5 on the two dials will be in line, etc. Thus while the dials are rotating in one direction the numerals appearing in the sight opening 88 will increase in value while the numerals appearing in the opening 89 will proportionately decrease in value.

It is to be understood that the calculating machine includes any desired number of units, each unit being controlled by the keys of one column. Furthermore each unit includes one rock shaft 13, one shaft 28, and the various parts mounted on and associated with these shafts as hereinbefore pointed out. In Figure 5 the shafts 13 and 28 of four different units have been shown in section and these same shafts have been illustrated in Figure 4. By referring to the said figure it will be noted that for the sake of compactness of construction the escape- 110 ment mechanisms on the different shafts 28 are disposed in staggered relation with any necessary changes in the location of gears to insure the proper carrying forward of motion from one unit to the other during the arithmetical operation. For the same reasons the positions of the gears 18 and 17 are changed so that they are staggered as 120 illustrated in Figure 4.

The construction of the machine is such that the adding mechanism will be operated upon the down stroke of a key of one or more of the different units at which time 5 energy will be stored so that during the upward or return strokes of the keys the carrying mechanism will be operated. The general action of the mechanism has been disclosed in Patent No. 1,309,535 issued to 10 me on July 8, 1919. Owing to certain differences between the construction of the present device and that of my patented structure the operation of the mechanism may be described as follows:

15 When one key 2 of a unit is depressed the lever 8 is actuated thereby, the extent of movement of the lever 8 depending on the position of the key operating it. During the downward movement of lever 8 the 20 master key 12 will, through its connection with the shaft 13, rock said shaft against the action of its spring 16 and cause the segment 17 to transmit motion through the lost motion mechanism to the shaft 28 belonging to said unit. If, by way of illustration, the depressed key belongs to the 25 "tens" column of the machine the rotation of the shaft 28 by the depression of the key will result in the transmission of motion through gears 48, 47 and 46 to the gear 45 of the mechanism belonging to the "hundreds" unit of the machine. The actuation of shaft 28 of the "tens" unit will cause the rotation of the dials 86 and 87 30 geared to said shaft, the number of numerals carried by said dial past the opening 88 being equal to the number displayed on the depressed key. For example if the dial is set at "0" and the "3" key is depressed 35 the numeral 3 will appear in the opening 88. If thereafter the "9" key is depressed the dial will be rotated so that the numerals will appear successively in the sight opening from "4" to "0" and thence to "2". 40 The difference in the amount of rotation of the dial is due to the fact that the rock shaft 13 is rotated different distances according to which key 2 is depressed, as before explained.

45 During the rotation of the shaft 28 of the "tens" unit the gear 45 of the "hundreds" unit is being rotated as before explained. Each time a key of the "tens" unit is depressed the projection 68 movable with its 50 shaft 13 travels away from the bell crank 69 cooperating therewith and, consequently, a spring 90 connected to said bell crank will shift the head 71 into one of the recesses 42 in the carry wheel of the "hundreds" unit, 55 thus holding it against rotation. The rotation of gear 45 of the "hundreds" unit will gradually elongate the spring 54 which will pull on the pin 53 and tend to rotate the carry wheel were it not held by the head 71.

60 The carry wheel is further held against ro-

tation at this time because the pin 53 bears against one end wall of the slot 52 in floating wheel 50 and this wheel cannot rotate because it is normally held by one of the pallets or levers 59. While the gear 45 of 65 the "hundreds" unit is being rotated by the mechanism of the "tens" unit the gear 65 of the "tens" unit is being rotated in properly timed relation with shaft 28 of said "tens" unit so that when the dial 86 of the "tens" 70 unit moves to "0" in the opening 88 the shoulder 63 on one of the cams 61 passes under the adjacent end of one of the pallets 59. Consequently said pallet will shift automatically under the action of its spring 62 75 so as to disengage from the projection 51 contacted thereby and allow the floating wheel 50 to rotate under the action of spring 56 which is fastened at one end to the floating wheel and at its other end to the held pin 53. Thus the back end of the slot 52 will come against the pin 53, thereby allowing the floating wheel to make a one-tenth revolution and bringing the next projection 51 against the head or projection 60 of the 80 other pallet which has been shifted to active position prior to the release of the first pallet. The foregoing action takes place when the key in the "tens" column is depressed and, as before stated, during the depression 85 of this key the bell crank 69 will shift into engagement with the carry wheel 73. Thus even though the floating wheel 50 can make a one-tenth rotation the carry wheel will be held. When the depressed key is released 90 and returns automatically to its normal position the projection 68 controlled thereby will come against the bell crank 69 and shift it back to its normal position. Thus the head 71 will move out of engagement with 95 the carry wheel and the tensioned spring 54 which is of greater strength than the spring 56 will pull the pin 53 back to the front end of the slot 52, thus causing the carry wheel 100 105 110 115 120 125 130 135 140 145 150 155 160 165 170 175 180 185 190 195 200 205 210 215 220 225 230 235 240 245 250 255 260 265 270 275 280 285 290 295 300 305 against the stop 82 where it will be held so as to prevent further rotation of the carry wheel. As the control wheel reaches this new position a spring 91 connected to the bell crank 79 will operate to swing the bell crank back into one of the recesses 42 and at the same time withdraw the finger from in front of the engaged projection and allow it to spring back against the stop 81 where it 10 is reset.

What is claimed is:—

1. In a calculating machine separate dial mechanisms each including a key actuated driving wheel, a floating wheel, a spring controlled by the driving wheel for storing energy, projections on opposite faces of the floating wheel in staggered relation, separate levers mounted for engagement with the projections on opposite sides of the 20 floating wheel respectively, and separate cams directly engaging the levers to shift them successively into wheel holding positions.

2. In a calculating machine separate dial mechanisms each including a key actuated driving wheel, a floating wheel, a spring for storing energy during the rotation of the driving wheel relative to the floating wheel, projections on opposite faces of the floating 30 wheel in staggered relation, separate levers mounted for movement about a common axis for engagement with the projections on the respective sides of the wheel, and key operated means for tilting the levers in properly timed relation to successively engage and release the projections on the respective sides of the floating wheel.

3. In a calculating machine carrying mechanisms each including a driving wheel, 40 a floating wheel, a carry wheel, a spring connection between the carry wheel and the driving wheel for storing energy during the movement of the driving wheel relative to the floating wheel, a spring connection 45 between the carry wheel and the floating wheel working in opposition to the first mentioned connection, separate levers, projections on opposite sides of the floating wheel and staggered for successive engagement by the respective levers, a key 50 actuated means for successively shifting said levers in properly timed relation to engage and release the projections on the respective sides of the floating wheel, and means released by the depression of a key for engaging the carry wheel to hold it against rotation until the key is returned to normal position.

4. In a calculating machine carrying 60 mechanisms each including a shaft, a driving wheel on the shaft for receiving motion from the shaft of an adjoining carrying mechanism, a control wheel secured to the shaft and having spaced projections, a carry 65 wheel having spaced recesses, a driving con-

nexion between the carry wheel and the control wheel, means controlled by the carry wheel for automatically stopping the control wheel on the completion of a predetermined movement thereof, a floating wheel, a spring connection between the carry wheel and the drive wheel, a spring connection between the carry wheel and the floating wheel, and separate, successively operating, rigid pallets cooperating with opposed faces 70 respectively of the floating wheel for intermittently releasing said wheel, the said spring connections working in opposition to each other.

5. In a calculating machine the combination with carrying mechanisms each including a carry wheel, a floating wheel, a driving wheel, and means for actuating the same, of a control wheel, a shaft operated thereby, pawl and ratchet mechanism transmitting motion from the carry wheel to the control wheel, a member normally engaging and shiftable by the carry wheel, projections on the control wheel, and means operated by said member for engagement with the projections successively to insure a step by step rotation of the control wheel and the shaft and to limit each rotation of said wheel and shaft to a predetermined degree. 95

6. In a calculating machine a key operated shaft, a dial unit including an escape mechanism having a carry wheel, a stop for the carry wheel, cooperating means on the stop and shaft for holding the stop normally disengaged from the carry wheel, and means for automatically shifting the stop into engagement with the carry wheel when the shaft is actuated by a key. 100

7. In a calculating machine, separate dial mechanisms, each including a key actuated driving wheel, a floating wheel, means controlled by the driving wheel for storing energy, separate series of projections on the floating wheel, separate levers mounted for engagement with the respective series of projections on the floating wheel, and separate cams directly engaging the levers to shift them successively into the wheel holding positions. 105

8. In a calculating machine, separate dial mechanisms each including a key actuated driving wheel, a floating wheel, means for storing energy during the rotation of the driving wheel relative to the floating wheel, separate series of projections on the floating wheel, separate levers mounted for movement about a common axis for engagement with the projections of the respective series, key operated means for tilting the levers in properly timed relation to successively engage and release the projections of the respective series. 120

9. In a calculating machine a control wheel, projections thereon, a carry wheel 125

having peripheral recesses, means for operating the carry wheel, means for transmitting motion from the carry wheel to the control wheel, a bell crank normally engaged in one of the recesses, a locking finger yieldingly carried by the bell crank and movable thereby to position between the

projections to prevent overthrowing of the control wheel, and stop device cooperating with the finger.

In testimony that I claim the foregoing as my own, I have hereto affixed my signature.

JAMES F. MAYS.
